MACHINE FOR PIERCING TUBES

Guy M. Hartsock and Harold S. Rounds, Detroit,
Mich., assignors to Mid-West Hydro-Pierce,
Inc., Detroit, Mich., a corporation of Michigan

Application March 9, 1942, Serial No. 433,948

14 Claims. (Cl. 164—89)

This invention relates to a machine for piercing tubes.

It is common practice to form holes in a tube by drilling. Drilling holes in a tube, and particularly where the holes are quite numerous, is not only uneconomical but also a slow process. It is the object of this invention to produce a machine for piercing holes in tubes which is economical, efficient, and capable of piercing holes at a much faster rate than by drilling the same.

The invention also contemplates a machine for piercing tubes which pierces an accurate, clean hole, which is simple in form and operation, and which automatically feeds the tube to the piercing dies, positions the tube in the dies, and removes the pierced tube from the dies.

In the drawings:

Fig. 1 is a vertical cross section of the machine showing the tube in the machine after it has been pierced and prior to withdrawing the punches from the dies. This section is taken along the line 1—1 of Fig. 2.

Fig. 2 is a longitudinal vertical section along the line 2—2 of Fig. 1.

Figs. 3 and 4 are sections along the lines 3—3 and 4—4 respectively of Fig. 1.

Fig. 5 is a section along the line 5—5 of Fig. 6.

Fig. 6 is a fragmentary elevation along the line 6—6 of Fig. 8.

Fig. 7 is a section along the line 7—7 of Fig. 6.

Fig. 8 is a vertical cross sectional view through the machine similar to Fig. 1 but with the punches retracted from the die and the tube about to be positioned in the die.

Fig. 9 is a schematic lay-out of the hydraulic circuit for operating the machine.

Fig. 10 is a detail view of the conveyor indexing mechanism.

The machine is designed for automatic operation. Accordingly, the tubes 1 are fed by means of a conveyor in the form of a pair of chains 2 which run around a pair of sprockets 3 positioned at the work feeding end of the machine and another pair of sprockets 4 positioned at the work discharge end of the machine. Sprockets 3 rotate about the horizontal shaft 5 and sprockets 4 rotate about the horizontal shaft 6. Each of the chains 2 are guided along an endless track 7 having straight portions 8 along the top side so that the tube will be accurately positioned in the piercing die as described below.

Each conveyor chain is provided with a plurality of circumferentially spaced work holders 9 provided with sockets 10. The holders 9 on the

one conveyor chain are accurately aligned with the holders on the other conveyor chain so that the longitudinal axis of the tube when presented to the dies is accurately aligned with the longitudinal axis of the dies. The tube is supported at each end in the sockets 10.

The conveyor is indexed with a step by step movement by means of a pawl 11 pivoted as at 12 on piston rod 13 which is connected to piston 14 operating in the hydraulic cylinder 15. Pawl 11 co-acts with a plurality of indexing pins 16 circumferentially spaced on plate 17 which is fixed on shaft 5 to index the conveyor. As the piston 14, Fig. 2, moves towards the right, the inclined end 18 of the pawl 11 rides over pin 16 (dotted line showing, Fig. 2) and then the hooked end of the pawl drops behind the pin 16, Fig. 10, so that upon the leftward or feeding stroke of the piston 14 the pawl indexes the pin and plate 17 120° from the position shown in Fig. 10 to the full line position shown in Fig. 2. Each indexing of the plate 17 moves the conveyor a distance equal to the distance from the center of one holder 9 to the center of the adjacent holder 9.

At the end of its indexing stroke pawl 11 rides along roller 19 which is pivotally supported on the conveyor frame 20. At the end of the indexing stroke pin 16, Fig. 2, is interengaged in the socket 21 of the hooked end of the pawl 11 and since pawl 11 rests on the roller 19, which has a fixed bearing support on the frame 20, pawl 11, roller 19 and pin 16 function together to lock the indexing plate 17 against counter-clockwise rotation, Fig. 2. Locking of the indexing plate 17 also locks the conveyor against counter-clockwise rotation and thus prevents the conveyor, due to inertia, from conveying the tube beyond the piercing dies.

The conveyor frame 20 is supported on the main frame 22 of the machine. Opposing supports 23 for the piercing heads are slidably supported on the main frame 22. Supports 23 are identical. As shown in Fig. 3, supports 23 is provided with slide-ways 24 which slidably engage parallel track members 25 mounted on frame 22. Support 23 is provided with hold-down plates 26 which slidably engage the under side of tracks 25 to hold the supports 23 on tracks 25. Each support 23 includes a circular plate portion 27 which supports a plurality of hydraulically operated piercing heads generally designated 28. The number of heads 28 which are circumferentially spaced about plate 27 and the spacing of these heads will depend upon the number of holes to be pierced in the tube and the spacing of these

holes circumferentially of the tube. As shown (Figs. 2 and 6), there are four piercing heads mounted on each plate 27 spaced 90° because of the fact that the holes to be pierced in tube 1 are 90° about the circumference of the tube. Slides 23 are moved into tube piercing position and retracted therefrom by pistons 29 which are reciprocatable in cylinders 30. Pistons 29 are provided with piston rods 31 which are adjustably connected to slides 23 as at 32. Cylinders 30 are fixed on the frame 22 as at 33 between the tracks 25.

Each piercing head comprises a cylinder 34, a piston 35 within the cylinder, and a piston rod 36 connected to the piston. The piston rod has fixed thereto a slide block 37 which slides in ways 38 so that during the piercing operation the piston rod 36 will slide in an accurate rectilinear path. A punch holder 39 is mounted in slide 37. The punches carried by the holders 39 are designated 40. As shown in Figs. 1 and 8, the heads mounted on the left hand plate 27 each carry a single punch 40 whereas the heads 28 mounted on the right hand plate 27 each carry two punches 40 spaced longitudinally of the tube. The number of punches carried by each head and their position is determined by the number of holes in the tube and their relative position. It so happens here, for purposes of description, that the right hand end of tube 1 requires twice as many holes as the left hand end of tube 1. During the piercing operation the tube 1 is supported internally by the mandrel 41; Fig. 5. The mandrel 41 is provided with an axial hole 42 into which the slugs of metal pierced out by punches 40 are discharged from holes 43. Mandrel 41 is secured by bolts 44 to plate 45 which in turn is secured by bolts 46 to the external die member 47. Die member 47 is secured by bolts 48 to plate 27. Die member 47 is provided with die holes 49 for punch 40 which accurately line up with die holes 43 in mandrel 41. During the punching operation the mandrel 41 supports the tube 1 internally so that the tube will be accurately pierced without deforming the tube.

After the slugs are discharged from the die holes 43 into the opening 42, they are discharged from the open end of mandrel 41 by ejector 50. The outer end of ejector 50 is piloted in bore 51 of plate 45 and the other end of the ejector 50 is fixed to the frame 22 of the machine as at 52 so that the ejector 50 is stationary but plate 27 moves relative to ejector 50 as the tube is fed into and discharged from the mandrel 41 and external die 47. For ejecting the tube from the mandrel 41 and die 47, the frame 22 has fixed thereon four ejectors 53 which slidably engage die 47 in guideways 54.

The piercing machine is provided with a hydraulic drive which is purchased on the open market and therefore will only be described generally. This drive comprises low and high pressure pumps 60 and 61 respectively, which are driven by electric motors. The outlet of the pumps are connected by pipes 62 and 63 and line 64 with a solenoid operated valve 65. As shown, solenoid valve 65 has been operated so that pressure line 64 is connected with line 66 which runs to cylinder 15. The oil under pressure from line 66 during each cycle of operation of the machine first moves piston 14 on its leftward or indexing stroke, Fig. 9, so that the conveyor 2 is indexed to the position shown in Fig. 2 with a tube 1 positioned in alignment with the mandrel 41 and outer die 47 which have not yet closed in on the

ends of the tube. After piston 14 reaches the end of its indexing stroke, then the pressure rises in lines 67 and 68 leading to cylinders 30. As the pressure rises in lines 67 and 68, pistons 29 move inwardly thereby moving slides 23 and plates 27 inwardly causing mandrels 41 to enter opposite ends of the tube 1 and dies 47 to move over the ends of the tube, as shown in Fig. 5. Inward movement of plates 27 also places the piercing heads 28 in piercing position.

As soon as the piercing heads are in position, the pressure increases in line 70. Slides 23 are provided with a projection 100 which closes switches 101 as the slides reach inward or piercing position so that at this time solenoid valve 71 is shifted to the right from the position illustrated in Fig. 9 so that this pressure is transmitted through line 72 to the circular distributing mains 73 mounted on plates 27. From the distributing mains 73 the liquid under pressure is distributed by line 74 to the ends of cylinders 34, thereby causing the punches 40 to move inwardly and pierce the end of the tube, as shown in Fig. 1.

As soon as the piercing operation is completed, pressure builds up in line 72 and cylinder 102 thereby closing switch 103 so that solenoid valve 71 shifts to the position shown in Fig. 9 thereby transmitting fluid under pressure from line 70 through line 80 to the circular distributing mains 81 mounted on the back of plates 27 and then through lines 82 into the lower ends of cylinders 34. At this time lines 74, 73, 72 and 84 become exhaust lines returning the exhaust liquid to the reservoir 85 as pistons 35 move outwardly to retract the punches from the tube and outer die to the position shown in Fig. 5.

As soon as the punches have been retracted, pressure builds in line 80 and cylinder 104 and switch 105 now closes so that solenoid valve 65 is shifted to the left from the position shown in Fig. 9 so that lines 66, 67 and 68 now become exhaust lines for exhausting cylinders 15 and 30 and pressure is admitted through lines 75 and 76 to the left hand end of cylinder 15 and 45 to the inner ends of cylinders 30. As liquid under pressure enters the left hand end of cylinder 15, piston 14 moves to the right thereby returning indexing pawl 11 to the position shown in Fig. 10. As liquid under pressure enters the inner ends of cylinders 30, pistons 29 move outwardly thereby moving slides 23 outwardly and withdrawing mandrels 41 from within the ends of the tube and withdrawing outer dies 47 from about the ends of the tube. As plates 27 move outwardly strippers 50 eject the punched out slugs from opening 42 in mandrel 41 and strippers 53 strip the end of the tubes from mandrels 41 and from the dies 47. Pressure now builds up in line 75 and cylinder 106 thereby closing switch 107 so that valve 65 now shifts to the position shown in Fig. 9, the operating cycle is completed, and a new tube is indexed into piercing position and the above described cycle automatically repeated.

We claim:

1. A machine for piercing tubes comprising in combination a support; a mandrel mounted on said support adapted to fit within the tube for supporting the same while being pierced, said support being slidable relative to the tube for positioning the mandrel within the tube and for withdrawing the mandrel from the tube, said mandrel having a chamber therein and an opening extending through a wall of the mandrel; a piercing tool adapted to pierce the tube and pass

through and be guided by the opening in the mandrel while piercing the tube, the said tool discharging the pierced out slug into the chamber of the mandrel, and an ejector operable in the chamber of the mandrel for ejecting the slug from the mandrel.

2. A machine for piercing tubes comprising in combination a support, a mandrel mounted on said support adapted to fit within the tube for supporting the same while being pierced, said support being slidable relative to the tube for positioning the mandrel within the tube and for withdrawing the mandrel from the tube, said mandrel having a chamber therein and an opening extending through a wall of the mandrel, a piercing tool adapted to pierce the tube and pass through and be guided by the opening in the mandrel while piercing the tube, the said tool discharging the pierced out slug into the chamber of the mandrel, and an ejector operable in the chamber of the mandrel for ejecting the slug from the mandrel, wherein the support also carries a die adapted to fit about the outside of the tube and the mandrel and having an opening through a wall thereof aligned with the opening in the mandrel through which the tool passes and in which the tool is guided during the piercing of the tube.

3. The combination as claimed in claim 2 including an ejector for ejecting the pierced tube from the outer die and mandrel.

4. A machine for piercing tubes comprising a slidable support, a mandrel mounted on the said support adapted to fit within the tube and support the same while being pierced, said mandrel having a radial opening therein, a tool carried by the sliding support and projectable through the tube and into the opening in the mandrel for piercing the tube, the said slidable support, mandrel and tool being slidable as a unit with respect to said tube into and out of piercing position.

5. The combination as claimed in claim 4 wherein the mandrel is provided with an axial opening into which the slugs pierced out of the tube fall, and an ejector stationary relative to the slidable support for ejecting the slugs from the opening in the mandrel as the mandrel is withdrawn from the tube.

6. A machine for piercing tubes comprising a holder for the tube, a support slidable axially relative to said tube, a die carried by said support, a piercing tool also carried by said sliding support, said piercing tool and die being adapted to be moved into piercing position with respect to said tube by an axial movement of the sliding support relative to said tube, an opening in the die member through which the tool is adapted to pass while piercing the said tube.

7. The combination as claimed in claim 6 including means for moving the slide member into piercing position with respect to the tube preparatory to piercing the tube, and means for operating the piercing tool to pierce the tube and remove the tool from the tube and die preparatory to withdrawing the sliding support and die from the pierced tube.

8. A machine for piercing tubes comprising a holder for the tube, a sliding support, a mandrel positioned on the support in axial alignment with the tube, a die mounted on the support and surrounding the mandrel, aligned radial openings in said die and mandrel, a piercing tool mounted on the support movable into and out of the said radially aligned openings, the said slid-

ing support being adapted to slide axially relative to said tube for inserting the mandrel within the tube and the die member about the tube preparatory to the piercing operation, and means for projecting the tool into said openings to pierce the tube and withdraw the tool preparatory to retracting the mandrel and die from the said tube.

9. The combination as claimed in claim 8 wherein the mandrel is provided with an opening into which the pierced out slugs fall, and means actuated as the mandrel is retracted from the tube for ejecting the slugs from the mandrel.

10. The combination as claimed in claim 8 including an ejector operable as the mandrel and die are withdrawn from the tube for ejecting the tube from between the mandrel and the outer die.

11. The combination as claimed in claim 8 wherein a hydraulic motor is mounted upon the sliding support and is connected to the piercing tool for projecting the tool through the tube to pierce the same and for retracting the tool from the pierced tube.

12. A machine for piercing tubes comprising a pair of opposed supports slidable relatively toward and away from each other, opposed dies carried by each of said supports, means for presenting a tube between the said dies when the sliding supports are moved relatively apart whereby as the slides move relatively toward each other the tube is moved into piercing relation with the dies, a piercing tool mounted on each of the slide members and adapted to pass through an opening in the die member for piercing the tube, and means for withdrawing the tool from the pierced tube preparatory to sliding the supports relatively away from each other to disengage the dies from the pierced tube.

13. A machine for piercing tubes comprising a holder for the tube, a conveyer upon which the holder is mounted, a support rectilinearly movable in a direction parallel to the longitudinal axis of said tube, a mandrel carried by said support, said conveyer transporting said holder and tube in a direction perpendicular to the longitudinal axis of the tube to position the tube in axial alignment with the mandrel preparatory to being pierced and for removing the tube out of piercing position after the same is pierced and the mandrel has been retracted, a piercing tool also carried by said rectilinearly movable support, said piercing tool and mandrel being adapted to be transported into piercing position with respect to said tube when the tube is in axial alignment with said mandrel by rectilinear movement of said support and the piercing tool and mandrel carried thereby toward said tube and axially of said tube whereby the mandrel telescopes with the tube to support the same during the piercing operation, said mandrel having an opening for receiving the tool during the piercing operation.

14. A machine for piercing tubes comprising a holder for the tube, a conveyer upon which the holder is mounted, a stationary frame, a support rectilinearly movable upon said stationary frame in a direction parallel to the longitudinal axis of said tube, a mandrel carried by said support, said conveyer transporting said holder and tube in a direction perpendicular to the longitudinal axis of the tube to position the tube in axial alignment with the mandrel preparatory to being pierced and for removing the tube out of piercing position after the same is

pierced and the mandrel has been retracted, a stationary stripper mounted on said frame on the same side of the said conveyer as the rectilinearly movable support and adapted to abut the end of the tube to strip the same from the mandrel as the mandrel is retracted, a piercing tool also carried by said rectilinearly movable support, said piercing tool and mandrel being adapted to be transported into piercing position with respect to said tube when the tube is in

10 axial alignment with said mandrel by rectilinear movement of the said support and the piercing tool and mandrel carried thereby toward said tube and axially of said tube whereby the mandrel telescopes with the tube to support the same during the piercing operation, said mandrel having an opening for receiving the tool during the piercing operation.
